BURNER

Filed July 6, 1925

UNITED STATES PATENT OFFICE.

OLOF A. TOFFEEN, OF CHICAGO, ILLINOIS.

BURNER.

Application filed July 6, 1925. Serial No. 41,501.

This invention relates to an improved burner adapted for use in boilers, furnaces and fire boxes generally of stationary and portable heating plants, said burner adapted to be supplied with coal dust by compressed air, steam or an atomizer or with oil by gravity feed, compressed air or an atomizer.

It is an object of this invention to provide a stationary burner adapted to be secured within the fire box of a boiler or furnace and further adapted to pre-heat the entering air by means of forced feed fuel delivered by means of a rotatable fuel distributor forming a part of said burner.

It is also an object of the invention to provide a stationary burner having a rotatable fuel feed device adapted to distribute coal dust or oil within the burner to pre-heated air entering the burner through predetermined paths.

It is a further object of this invention to provide a burner for use on a fire grate, said burner being constructed of selected materials adapted to withstand the great heat to which the parts are subjected.

It is furthermore an object of the invention to provide an improved oxygenator adapted to permit entering air to follow a predetermined course to cause pre-heating of the air as it is carbureted with coal dust or oil to cause a substantially complete combustion of the fuel and a consequent reduction of the escaping volatile matter thereby obviating the production of smoke.

It is an important object of this invention to provide a stationary burner for boiler and furnace fire boxes, said burner constructed to deliver pre-heated air into the combustion chamber of the burner to permit the pre-heated air to be carbureted with fuel delivered by a rotating fuel feed device and constructed of a selected great heat withstanding material as is also the inner casting of said burner.

Other and further important objects of this invention will be apparent from the disclosures in the specification and the accompanying drawings.

The invention (in a preferred form) is illustrated in the drawings and hereinafter more fully described.

On the drawings—

Figure 1 is a horizontal section taken through a burner embodying the principles of this invention; and

Figure 2 is a vertical section taken on line II—II of Figure 1.

As shown on the drawings:

The reference numeral 1 indicates a cast iron or steel bottom or base plate provided with a circular flange or bead 2 and having a plurality of distributed air inlet apertures or ports 3. The base plate 1 is also provided with an ash or oil discharge opening 4. Positioned beneath the middle portion of the base plate 1 to support the same is a chambered housing or pedestal 5. Mounted within the pedestal 5 are two ball bearings 6 affording a bearing for a vertical hollow shaft 7. The upper end of the hollow shaft 7 projects through the base plate 1 and into a steel bearing sleeve or collar 8 resting upon the top end of the pedestal 5. Engaged on the hollow shaft 7 within the pedestal 5 is a bevel gear 9 which receives a drive from a bevel drive gear 10 meshing therewith. The bevel drive gear 10 is secured on one end of a shaft 11 journaled in a ball bearing 12 within an extension or arm 13 of the pedestal 5. Connected with the lower end of the pedestal 5 is a fuel supply pipe 14 connected with an oil or coal dust supply tank or bin respectively located in any convenient position. When oil is used as a fuel it may be fed into the lower open end of the pipe 7 by compressed air, gravity or by means of an atomizer. When pulverized coal is to be used as the fuel, the coal dust may be fed to the pipe 7 by an atomizer, compressed air or by the use of steam.

The steel sleeve 8 projects upwardly through a central opening 15 formed in a deflector plate or baffle plate 16 constructed of a steel alloy. The baffle plate 16 is formed with an integral peripheral groove 17 the outer margin of which terminates in an upwardly directed circular flange 18. The groove 17 is provided with an opening 19 which registers with the discharge opening 4. Formed integrally in the baffle plate groove 17 at spaced intervals are a plurality of notched ribs or seats 20 adapted to afford supports for an inner cylindrical casing or housing 21 comprising a plurality of interfitting sections constructed of a particular material which is a carborundum product or a fused silicon carbide, said material adapted to be heated to approximately 4250° C. without causing any signs of deterioration of the material. The inner casing 21 is provided

with a plurality of inclined ports or air passages 22 disposed at spaced intervals around the upper portion of the casing. A bead 23 is formed around the upper margin of the 5 casing 21.

Seated upon the base plate 1 to the inside of the bead 2 is an outer casing or housing 24 formed of a special steel alloy or adapted to be made of carborundum. The outer 10 casing 24 has the upper portion of conical shape to permit the upper edge to fit beneath the bead 23 of the inner casing 21.

Supported upon the upper end of the sleeve 8 is a rotatable burner or fuel distributor comprising a bottom plate or disk 25 and an upper plate or disk 26. The disks 25 and 26 are constructed of carborundum or fused silicon carbide and have a plurality of registering holes to permit the two 20 disks to be secured together by means of bolts 27 or other suitable means. The abutting faces of the disks 25 and 26 are provided with angled grooves having enlarged outer recesses 28. A four way union 29 is 25 secured in place between the disks 25 and 26 at the middle portions thereof. Secured in each arm of the union 29 is an elbow pipe 30 the outer end of which is directed slightly upwardly as illustrated in Figure 30 2 with the end of the pipe communicating with the recess 28. The elbow pipes are clamped between the distributor disks 25 and 26. The union 29 is also provided with a downwardly directed arm 31 which fits 35 around the upper projecting end of the pipe 7 within a boss 32 integrally formed on the bottom of the lower distributor disk 25. The boss 32 rests upon the upper end of the sleeve 8.

40 The improved burner acts as an oxygenator and smoke eliminator and is adapted to be mounted within a boiler or furnace fire box. A motor or other driving means may be connected with the drive shaft 11. 45 while the pipe 14 may be connected with the fuel supply. The fuel, for example, oil, may be fed by gravity, compressed air or by means of an atomizer into the lower chamber of the pedestal 5 thereby permitting the fuel to pass through the pipe 7 into the distributor pipes 30. From the pipes 30 the fuel is directed through the recesses 28 in an upwardly inclined direction against the inner walls of the inner casing 21. The revolving distributor causes the fuel to be distributed centrifugally to carburate the air entering the inner casing ports 22 and the air which passes upwardly 50 through the ports 33 of the baffle plate 16. 55 Air entering through the base plate ports 3 also passes upwardly between the outer steel shell or housing 24 and the flange 18 of the baffle plate 16. The air passes over the top of said flange and is directed between the inner casing 21 and said flange 60 65

18 into the groove 17 and is admitted into the lower part of the combustion chamber beneath the rotatable distributor. It will be noted that air is thus permitted to enter the combustion chamber below and above 70 the rotatable distributor to be carbureted with the fuel which is distributed by the revolving distributor 25-26.

When the carbureted air is ignited the resulting flames act to heat the carborundum or fused silicon carbide inner casing 21 and the distributor disks 25 and 26 to an extremely high temperature. The casing 21 and the distributor 25-26 readily absorb and retain the heat. The baffle plate 16 and the outer shell 24 are also heated by the combustion taking place within the chamber of the inner casing and thereby causes the air entering the base plate ports 3 to be preheated in the space afforded between the 80 outer shell 24 and the inner casing 21 before said air passes through the ports 22 and through the space between the flange 18 and the inner casing 21. It will thus be noted that the preheated air is delivered above and below the rotatable fuel distributor 25-26 and when said air is carbureted with the fuel issuing from the ends of the pipes 30 extremely hot flames are produced and are discharged through the top 90 of the burner. The degree of heat produced is so intense that the oxygen in the air is preheated, thus permitting the same to readily unite with the fuel gases and the volatile carbon products to cause a substantially 95 complete combustion of the fuel thereby obviating the production of smoke.

The base plate 1 and the outer shell 24 form an outer housing, while the baffle plate 16 and the inner shell 21 afford an inner housing within which the fuel distributor is rotatably mounted. The inner shell 21, the distributor 25-26 and the outer shell 24 are the parts which are subjected to extremely high temperatures and are consequently constructed of the carborundum product or fused silicon carbide which is adapted to retain and transmit the heat without any deteriorating effects as do other materials when used under similar circumstances. The outer shell 24 may also be constructed of a special steel alloy similar to that used in the construction of the baffle plate 16 and the sleeve 8.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A burner comprising a support, an apertured base plate thereon, a fuel distributor rotatably supported on said sup-

- port, means in said support connected to 5
rotate said distributer, an apertured baffle
plate on said base plate, an inner apertured
casing supported on said baffle plate and
surrounding said distributer, and an outer
casing supported on said base plate and en-
gaging said inner casing.
2. A burner comprising a support, an
apertured base plate thereon, an outer cas-
ing supported on said base plate, an
apertured baffle plate supported on said base
plate, an upwardly directed flange formed
on said baffle plate, an apertured inner cas-
ing supported on said baffle plate and con-
tacting said outer casing, said inner casing
being positioned within said baffle plate
flange and spaced therefrom, a fuel dis-
tributer in said inner casing, and means in
said support connected to rotate said dis-
tributer.
3. A burner comprising an apertured
outer housing, an apertured grooved baffle
plate therein having an integral upwardly
directed flange, seats formed on said baffle
plate, an apertured inner casing supported
on said seats and constructed of a carborun-
dum product, said inner casing being spaced
from said flange to afford an air passage
between said flange and said inner casing,
a fuel distributer within said inner casing
covered with a carborundum product, and
means connected with said distributer to
rotate the same.
4. A burner comprising an apertured
outer housing, an apertured inner casing
contacting the upper edge of said housing
and otherwise spaced therefrom, a fuel dis-
tributer in said casing, and a covering of
fused silicon carbide for said fuel dis-
tributer.
5. A burner comprising an apertured
outer housing, an apertured inner casing
constructed of a carborundum product, an
apertured and grooved baffle member sup-
porting said casing, a flange on said member
surrounding said casing and spaced there-
from, a sleeve projecting into said housing
and through said baffle member, a fuel sup-
ply pipe projecting through said sleeve, a
grooved fuel distributer supported on said
sleeve and constructed of a carborundum
product, and a plurality of fuel distribut-
ing pipes in said grooved distributer con-
nected to communicate with said fuel sup-
ply pipe.
6. A burner comprising a hollow support,
a fuel pipe journaled therein and project-
ing therefrom, means for rotating said fuel
pipe, a fuel supply pipe connected with said
support for delivering fuel to said first
mentioned fuel pipe, an apertured base
member on said support, an outer casing
seated on said base member, a sleeve resting
on said support and surrounding a portion
of the projecting part of said first men-
- tioned fuel pipe, an apertured and grooved
inner plate supported on said base member,
said inner plate having an integral flange
spaced from the inner walls of said outer
casing, a sectional inner casing supported on
said inner plate and spaced from said flange,
said inner casing being constructed of a
carborundum product and having a plural-
ity of air passages therein; a union secured
on the upper projecting end of said first
mentioned fuel pipe, a plurality of fuel dis-
tributing pipes connected with said union,
and a carborundum product covering said
union and said distributing pipes.
7. A burner comprising a rotatable fuel
distributer constructed of a carborundum
product, fuel pipes embedded therein, fuel
supply means connected with said pipes, an
outer housing having air inlet openings
therein beneath said distributer, an aper-
tured inner plate within said housing be-
neath said distributer, a grooved portion
integally formed thereon, a flange integral
with said grooved portion, and a car-
borundum product casing supported in said
grooved portion of the inner plate and
spaced from said flange to afford an air
passage, said casing having a plurality of
air passages therein above the level of said
distributer.
8. A burner comprising an apertured
housing, a fuel distributer movably mounted
therein, grooved insulating plates fitting
over the distributer to enclose the same, and
a casing between said housing and said
distributer, said casing having air openings
therein adapted to supply air below and
above said distributer.
9. A burner comprising a rotatable fuel
distributer, an apertured casing surround-
ing the same, an apertured flanged plate
spaced from said casing and positioned be-
neath said distributer and said casing, an
apertured outer housing enclosing the dis-
tributer and casing, means for rotating the
distributer, and means adapted to deliver
fuel through said distributer and into said
casing to permit the fuel to be mixed with
the air entering said casing from below and
above said distributer.
10. A burner comprising an outer housing
having the upper margin deflected in-
wardly, an air passage casing therein con-
tacted by said deflected margin of said outer
housing, a grooved distributer covering in
said casing constructed of a refractory ma-
terial, a plurality of connected fuel distribut-
ing pipes seated in said grooved covering,
means for rotating the distributer pipes and
said covering, and means for feeding fuel
through said pipes into said casing.
- In testimony whereof I have hereunto
subscribed my name.

OLOF A. TOFFTEEN.
